UNITED STATES PATENT OFFICE.

LOUISE E. VARNI-GARDINIER, OF SOUTH NORWALK, CONNECTICUT.

DESIGN FOR A MONEY-BELT.

SPECIFICATION forming part of Design No. 29,490, dated October 18, 1898.

Application filed June 11, 1898. Serial No. 683,386. Term of patent 3½ years.

To all whom it may concern:

Be it known that I, LOUISE E. VARNI-GARDINIER, a citizen of the United States of America, and a resident of the city of South Norwalk, county of Fairfield, State of Connecticut, have invented and produced an original Design for a Money-Belt, of which the following is a specification, reference being made to the accompanying drawings.

Figure 1 is a plan view of a money-belt showing my design. Fig. 2 is a sectional view taken on the line $\alpha\alpha$ of Fig. 1.

The main body of the aforesaid money-belt

is in the form of a parallelogram, the ends of which are composed of curvilinear isosceles triangles, the vertices of which are circular.

Having described my design, what I claim as new, and desire to secure by Letters Patent, is—

The design for a money-belt, as herein shown and described.

LOUISE E. VARNI-GARDINIER.
